Primary Examiner—Bernard Ansher*Assistant Examiner*—M. Siegel[57] **CLAIM**

The ornamental design for a pill dispenser housing, as shown and described.

DESCRIPTION

FIG. 1 is a perspective view of a pill dispenser housing showing my new design;

FIG. 2 is a top plan view thereof;

FIG. 3 is a front elevational view thereof;

FIG. 4 is a right side elevational view, the left side elevational view being a mirror image thereof;

FIG. 5 is a back elevational view thereof; and,

FIG. 6 is a bottom plan view thereof.

FIG. 1

FIG.2
